LIQUID FUEL BURNING APPARATUS

Joseph R. Kirkpatrick, South Euclid, Ohio, assignor to Perfection Stove Company, Cleveland, Ohio, a corporation of Ohio

Original application April 15, 1939, Serial No. 268,138. Divided and this application October 26, 1940, Serial No. 363,022

10 Claims. (Cl. 158—36)

This application is a division of one filed by me on April 15, 1939, Serial No. 268,138.

The invention pertains to liquid fuel burning apparatus that is especially suitable for use in furnaces of heating systems for houses or other buildings, and whose operating range includes low and relatively higher fires, and in which, through suitable fuel feeding and governing means, the burner is supplied with fuel—at no time, so long as the apparatus is in operation, with less than enough to sustain operation at low fire, and at other times, with a sufficiently increased amount of fuel to produce higher fires.

Customarily, in apparatus of the class to which the invention relates, liquid fuel of a rather heavy grade is used, such as that known as fuel oil; and at low fire, which practically amounts to pilot flame, very little fuel is required. For example; in the average size furnace burner, from one-half to one gallon of fuel is fed every 24 hours for the purpose of sustaining operation at low fire, and this amounts to very considerably less than one drop per second. Consequently, uniform feeding of the fuel at so low a rate represents a problem rendered difficult by several factors including variation in viscosity of different fuels; in the differences in viscosity of the same fuel at different temperatures, or the presence of sediment or foreign matter in the fuel. Under any circumstances, and especially those requiring accurate feeding of a very small quantity of fuel, the customary control of the flow by means of orifices (as is the case in practically all types of valves) is quite unsatisfactory and unreliable.

It is the fundamental object of my invention to provide liquid fuel burning apparatus of the character referred to in which the fuel is volumetrically fed—that is to say, is fed in measured quantities. In the presently disclosed embodiment of the invention, the volumetric feeding means comprises a plurality of dippers.

The invention may be defined, broadly, as comprising, with a liquid fuel burner and a source of liquid fuel supply, a fuel feeding and governing system through which the source communicates with the burner, and a part of which system serves as a reservoir to which fuel is delivered from the source, and a delivery part that communicates with the burner and that is separated by a barrier from the reservoir part so as to prevent natural flow of the fuel directly from the reservoir part to the delivery part. A substantially constant fuel level is maintained in the reservoir part, desirably by a suitable liquid level

control, and measured quantities of fuel are transferred from the reservoir part to the delivery part of the system by suitable transfer means, as by the dippers above mentioned, the fuel proceeding from the delivery part to the burner by gravity.

A motor or other appropriate means—desirably a small electric motor—has suitable driving connection with the dippers for oscillating the same, the one for supplying fuel to the low or pilot fire, according to the present embodiment of the invention, being constantly actuated so long as the apparatus is in operation.

Another object of the invention is to provide an automatic control by means of which the apparatus is caused to operate under certain conditions at intermediate fire, so to speak, thereby to maintain a given temperature, within rather close limits, in a space to be heated—as in a room, apartment or other enclosure—and which, in case the temperature of said space drops below a predetermined value, will act to cause an increase in the fuel supply to the burner so as to produce a higher fire; and in case the temperature of said space rises above a predetermined value, will function to suspend operation of all but the feeding means that supplies fuel for low or pilot fire, thereby to reduce the heat output of the apparatus.

A further object is to provide, in an automatically controlled fuel feeding apparatus of the character described, means for effecting delivery of fuel to the burner in sufficient quantity to sustain operation thereof at approximately intermediate fire in case of failure of the automatic control system, as, for example, by the stoppage or suspension of the supply of current, in case the control system is electrical.

A still further and more limited object of the invention is to provide fuel feeding and governing means in the form of a compact unit that is convenient of incorporation in a liquid fuel burning apparatus and is so constructed as to facilitate assembly and installation and that is efficient and reliable in operation.

An additional object is to provide a simple and convenient adjustment for varying the feeding capacity of the volumetric fuel feeding or transfer means.

The foregoing objects, with other and more limited ones hereinafter appearing, are attained in the embodiment of the invention illustrated in the accompanying drawings wherein Fig. 1 is a more or less diagrammatic representation of a liquid fuel burning apparatus incorporating the

invention; and Fig. 2 is a detail in perspective, with parts broken away, of the volumetric fuel feeding or transfer means.

The installation diagrammatically illustrated in Fig. 1 may be a part of a heating system for dwellings or other buildings and desirably involves means for automatically controlling the operation of the burner so as to maintain, in the space or apartment heated by the system, a substantially constant temperature within relatively close limits, notwithstanding variations in outside temperature or other exterior influences.

According to the present illustration, the burner is of the pot or bowl variety and is designated, generally, by the reference character A. It comprises a bowl 1 that is suitably supported with its top wall 2 in spaced relation to the bottom wall 3 of a combustion chamber 4. Said walls have aligned openings shown as surrounded by depending flanges 2^a and 3^a, that are in concentric, spaced relation to each other and define a slot 5 for the admission of secondary air to the burner bowl, as will hereinafter more fully appear. Primary air is admitted to the bowl through perforations 6 in the peripheral wall of the bowl. A relatively large lighting and cleanout opening is formed in said peripheral wall and the same is surrounded by a radially projecting neck 8 normally closed by a plug 9 shown as having a bayonet joint connection with the neck. The combustion apparatus comprising the bowl 1 and the chamber 4 may be that of a furnace of appropriate type for use in systems of the class above mentioned. For more detailed information on such apparatus, reference may be had to Letters Patent No. 1,944,593, dated January 23, 1934; No. 1,979,865, dated November 6, 1934; No. 1,987,179, dated January 8, 1935, and No. 2,000,884, dated May 7, 1935.

Liquid fuel is supplied to the burner A from a source B (represented as a tank) through a fuel feeding and governing system C (Fig. 1). A conduit 10 leads from said source to the system, and a conduit 11 leads from the system to the burner, the latter conduit being shown as opening through the bottom wall of the bowl 1. The system involves a reservoir part, to which fuel is supplied through said conduit 10, and a delivery part that communicates with the burner through the aforesaid conduit 11. A liquid level control tends to maintain a constant liquid level in the reservoir part, as will hereinafter more fully appear.

The fuel from the conduit 10 enters a float chamber 12 through a port 13. The passage of fuel through said port is controlled by a valve 14 that is depressed and closed by a float 15 through the intervention of a lever 16 fulcrumed on a pivot pin 17 that is suitably supported in a fixed position within the float chamber, as by and between the opposed side walls thereof. A spring 18 tends to open the valve in opposition to the action of the float. By this control means, the level of liquid in the reservoir part of the system is maintained substantially at the elevation indicated by the dot-and-dash line a—a.

What has been referred to as the reservoir part of the system includes, also, the receiving compartment or reservoir 20 of a vessel 21, said compartment being separated from an outlet compartment 22, or more generally, the delivery part of the system, by a barrier or partition 23 that extends from the bottom of the vessel to a height a material distance above the maximum liquid level indicated by the dot-and-dash line

a—a. Communication between the float chamber 12 and the reservoir 20 is established through a conduit 25. The outlet compartment 22 of the vessel 21 is communicatively connected to the burner A through the before-mentioned conduit 11; and a by-pass between the reservoir part of the system—specifically, conduit 25—and the delivery part of the system—in the present instance, the conduit 11—is provided by a conduit 27 that contains valve means comprising a casing 28 and a valve member 29, the latter being in the form of a tube having a V-notch 30 at its lower end in the region of the diaphragm 31 of the valve casing. The casing includes a sleeve 32 wherein the stem portion of the valve member is housed and whose open top is a substantial distance above the maximum liquid level in the system. The valve is normally held in closed position by a solenoid 35, while a spring 36 tends to shift the valve to open position when the solenoid is deenergized, these actuating elements being shown as operatively connected to the valve member 29 through the medium of a bell crank lever 37. The full open position of the valve is determined by an adjustable stop 38.

Supported by the vessel 21 a material distance above the partition 23 is a channel bar 40, best shown in Fig. 2; and through square holes in the bottom flange of said channel bar are guided, for vertical adjustment, hangers 41. The hangers, which are square in cross section and are of a size to slidably fit the aforesaid holes, are adjustably supported by screws 42 that are threaded in axial recesses in the upper ends of the hangers and extend freely through holes in the top flange of the channel bar 40. Pivoted connected to the lower ends of the hangers 41 are the trough-like buckets or dippers 45, 46 and 47, the size and capacity of the last mentioned dipper being considerably greater than the dipper 46, while the dipper 46 is of somewhat greater capacity than the dipper 45. The dipper 45 serves to supply fuel to the burner in sufficient quantity to sustain operation at low or pilot fire. As will more fully appear hereinafter, the dipper 46 supplies the additional fuel necessary to sustain operation of the burner at intermediate fire, while the dipper 47 further increases the fuel supply to that necessary to cause the burner to operate at high fire.

Shown (in dotted lines) as supported by and exteriorly of an upwardly extended portion of one of the side walls of the vessel 21 is an electric motor 50 whose drive shaft 51 is extended through an aperture in the wall extension and has fastened to it inwardly beyond said extension a pinion 52 that meshes with a spur gear 53, journaled on a stud 54 that projects inwardly from said wall extension. A crank pin 55 on the gear 53 is operatively connected to the dipper 45, near the free end of the latter, by a connecting rod or link 56. Fastened to the outer end of the motor shaft 51, beyond the pinion 52, is a double crank 57, the diametrically opposed pins whereof are designated 58 and 59. These respective crank pins extend freely through slots in connecting rods or links 60 and 61, the former being attached to the bucket 46 and the latter to the bucket 47.

Secured to and depending from an overhanging portion 64 of the upwardly extending end wall of the vessel 21 are thermostatic elements or bimetal strips 65 and 66, by the lower free ends of which are carried latch members 67 and

68, respectively, for holding engagement with extensions 70 and 71 on the respective dippers 46 and 47. Electric heaters 13 and 74, in the nature of resistance coils, are suitably attached to the respective thermostatic elements or strips 65 and 66. When the thermostatic elements or strips are cold, so to speak, they occupy the positions indicated in the drawings, element 66 being in a position to cause the latch member 68 thereof to engage beneath the extension 71 and sustain the dipper 47 in elevated position; while the element or strip 65 is normally in a position to retain the latch member 67 beyond reach of the extension 70 on dipper 46.

The electric circuit of the automatic control system for the apparatus includes a transformer 80, and a room thermostat 81. The two legs of the main or house circuit of 110 volts, for example, are represented by the conductors 82 and 83, the former including a switch 84. This circuit also includes the winding of the previously mentioned solenoid 35. The main circuit is provided with two branches, one represented by conductors 85 and 86 and including the primary winding 80^a of the transformer 80, and the other, represented by conductors 87 and 88 and leading to the aforesaid motor 50. One side of the secondary winding 80^b of the transformer 80 is connected through a conductor 90, with the movable contact element 91 of the room thermostat 81, while the other side of said winding has connection, through a conductor 92, with the heaters 13 and 74. The former heater is placed in circuit, through a conductor 93, with the contact 94 of the room thermostat, while contact 95 thereof is connected, through the conductor 96, with the heater 74.

The burner, under given conditions which may be regarded as normal, operates on fuel supplied by the two dippers 45 and 46, the heat produced by the apparatus under these circumstances being sufficient to maintain a room temperature of the desired range, under the influence of which the movable contact element 91 of the room thermostat remains in neutral position. Should the room temperature rise beyond the predetermined range the movable contact element 91 will swing to the left and engage contact 94, closing the circuit to the heater 13 and under the influence of the energized heater, the thermostatic element 65 will warp in the direction to bring the latch member 67 into the path of the extension 70 thereby to retain the dipper 46 in inactive, elevated position while the crank pins 58 and 59 play idly within the slots in the connecting rods or links 60 and 61. This leaves only the dipper 45 in operation, and this will supply sufficient fuel to the burner to sustain operation thereof at a low fire. Under these circumstances and the influence of a relatively lower outside temperature, the room temperature will drop, causing the movable element 91 to withdraw from the contact 94, thereby to interrupt the supply of current to the heater 13, allowing the thermostatic element 65 to cool and withdraw the latch member 67 from the extension 70, thus throwing the dipper 46 back into operation.

In the event the outside temperature continues to fall, similarly affecting the room temperature sufficiently to cause the movable contact element 91 of the room thermostat 81 to swing over into engagement with contact 95, a circuit will be established through heater 74, causing it to warp the thermostatic element or bimetal strip 66 in a direction to withdraw the latch member 68

from holding engagement with the extension 71, freeing the dipper 47 so that it may be oscillated through the action of the crank 59, thereby to increase the fuel supply and cause the burner to operate at high fire, this condition continuing until the temperature affecting the room thermostat has risen to within the aforesaid predetermined range, under which circumstances the contact element 91 will withdraw from contact 95, opening the circuit to the heater 74 so that the thermostatic element or strip 66 may cool and resume its former position wherein the latch member 68 engages the extension 71 and retains the dipper 47 elevated and out of operation.

Should the electric circuit that supplies current to the automatic control system fail from any cause, thereby to deenergize the motor 50 and throw the fuel feeding and governing system out of commission, the solenoid 35 will likewise be deenergized, whereupon the spring 36 will open the emergency valve 29, permitting a practical amount of fuel to by-pass the multiple volumetric feed comprising the buckets or dippers 45, 46 and 47 and sustain operation of the burner until the difficulty is rectified and the system returned to normal operation. Through the adjustable stop 38 the emergency valve 29 may be set to feed fuel in sufficient quantity to sustain operation of the burner at a stage equivalent to intermediate fire.

By reason of the fact that the top of the valve casing 32 is a substantial distance above the maximum liquid level in the system, a stuffing box or other seal is rendered unnecessary between the valve member 29 and the casing 32 and freedom of action of the valve is assured.

While I have specifically described a practical embodiment of the invention, I wish it to be understood that I do not limit myself to the structural character thereof further than required by the scope of the appended claims.

Having thus described my invention, what I claim is:

1. In combination, a liquid fuel burner, a source of liquid fuel supply, a fuel feeding system, a barrier separating said system into a reservoir part to which fuel is supplied from said source and a delivery part from which fuel flows to the burner, power operated means acting to periodically transfer fuel from the reservoir part past said barrier to the delivery part in sufficient amount to sustain operation of the burner at low fire, further power operated means for periodically transferring fuel from the reservoir part past said barrier to the delivery part in a sufficiently increased amount to produce higher fire, control means governing the action of the power operated means, communicative connections by-passing the aforesaid barrier and through which fuel may flow from the source to the burner, a valve in said connections biased toward open position, power operated means for retaining said valve closed, and a source of power common to all said power operated means.

2. In combination, a liquid fuel burner, a source of liquid fuel supply, a fuel feeding system, a barrier separating said system into a reservoir part to which fuel is supplied from said source and a delivery part from which fuel flows to the burner, means maintaining a substantially constant fuel level in said reservoir part, power operated means acting to periodically transfer measured amounts of fuel from the reservoir part past said barrier to the delivery part in sufficient quantity to sustain uninterrupted opera-

tion of the burner at low fire, further power operated means for periodically transferring measured amounts of fuel from the reservoir part past said barrier to the delivery part thereby to produce higher fire, and control means for throwing said further power operated means into and out of operation.

3. In combination, a liquid fuel burner, a source of liquid fuel supply, a fuel feeding system, a barrier separating said system into a reservoir part to which fuel is supplied from said source and a delivery part from which fuel flows to the burner, means maintaining a substantially constant fuel level in said reservoir part, power operated means for periodically transferring measured amounts of fuel from the reservoir part past said barrier to the delivery part in sufficient quantity to sustain operation of the burner at low fire, further power operated means for periodically transferring measured amounts of fuel from the reservoir part past said barrier to the delivery part thereby to produce higher fire, a source of power from which all said power operated means receive their power, control means for throwing said further power operated means into and out of operation, communicative connections by-passing the aforesaid barrier and through which fuel may flow from the source to the burner, a valve in said connections biased toward open position, and power means operatively connected to and capable of retaining said valve closed, said power means being subjected to the aforesaid source of power.

4. In combination, a liquid fuel burner whose operating range includes low and relatively higher fires, a source of liquid fuel supply, a fuel feeding system, a barrier separating said system into a reservoir part to which fuel is supplied from said source and a delivery part from which fuel flows to the burner, communicative connections by-passing said barrier, a plurality of mechanical means arranged to dip into said reservoir part and periodically transfer measured amounts of fuel therefrom past the barrier to the delivery part, power means for operating said mechanical means, control means for throwing different ones of said mechanical means into and out of operation according to the size fire required, a source of power for said power operated means, a valve in the aforesaid connections biased toward open position, and power means subjected to said source of power and serving when energized to hold said valve closed whereby, upon failure of the power, the valve is disposed in open position to permit fuel to flow from the reservoir part of the system to the burner.

5. In combination, a liquid fuel burner whose operating range includes low and relatively higher fires, a source of fuel supply, a fuel feeding system through which said source communicates with the burner, a barrier separating said system into a reservoir part to which fuel flows from said source and a delivery part from which fuel flows to the burner, a liquid level control tending to maintain a constant fuel level in said reservoir part, a plurality of power driven fuel receiving means arranged to dip into said reservoir part and periodically transfer measured amounts of fuel therefrom to the delivery part of the system, one of said means acting continually and being of a capacity to supply sufficient fuel to the burner to sustain operation thereof at low fire, and an instrumentality for effecting actuation of additional of said means thereby to deliver more fuel

from the reservoir part to the burner so as to produce higher fire.

6. In combination, a liquid fuel combustion device whose operating range includes low, intermediate and high fires, a source of liquid fuel supply, a fuel feeding system through which said source communicates with the combustion device, a barrier separating said system into a reservoir part to which fuel flows from said source and a delivery part from which fuel flows to the burner, three power operated volumetric fuel feeding means incorporated in said system the first of which transfers fuel from the reservoir part to the delivery part in sufficient quantity to sustain operation of the combustion device at low fire, the second of which transfers enough additional fuel to produce intermediate fire, and the third of which transfers the further additional amount of fuel necessary to produce high fire, electrical means having operative connection with the volumetric fuel feeding means and serving to actuate the first of said means continually, holding means for restraining the second and third means from action, that associated with the second means being biased toward ineffective condition and that associated with said third means being biased toward effective condition, an electrical device associated with each holding means, a thermostatic switch subjected to the temperature of the space heated by the combustion device, an electrical circuit including said thermostatic switch, the said electrical means and said electrical devices so organized and arranged that when said temperature rises above a predetermined range it will cause the energization of the device associated with the holding means of the second fuel feeding means and cause said holding means to assume effective condition, and when the said temperature falls below the predetermined range it will cause energization of the electrical device associated with the holding means of the third fuel feeding means causing said holding means to become ineffective.

7. In combination, a liquid fuel combustion device whose operating range includes low, intermediate and high fires, a source of liquid fuel supply, a fuel feeding system through which said source communicates with the combustion device, a barrier separating said system into a reservoir part to which fuel flows from said source and a delivery part from which fuel flows to the burner, three volumetric fuel feeding means incorporated in said system the first of which transfers fuel from the reservoir part to the delivery part in sufficient quantity to sustain operation of the combustion device at low fire, the second of which transfers enough additional fuel to produce intermediate fire and the third of which transfers the further additional amount of fuel necessary to produce high fire, electrical means having operative connection with the volumetric fuel feeding means and serving to actuate the first of said means continually, the second and third means being capable of being restrained from action, thermostatic latches for so restraining said second and third means, that of the second means assuming effective condition when heated and that of the third means assuming ineffective condition when heated, an electrical heater associated with each of said latches, a thermostatic switch subjected to the temperature of the space heated by the combustion device, an electrical circuit including said thermostatic switch, the said electrical means

and said electric heaters so organized and arranged that when said temperature rises above a predetermined range it will cause the energization of the heater associated with the latch of the second fuel feeding means, and when the said temperature falls below said predetermined range it will cause energization of the heater associated with the latch of the third fuel feeding means.

8. In combination, a liquid fuel burner, a source of liquid fuel supply, a fuel feeding system, a barrier separating said system into a reservoir part to which fuel is supplied from said source and a delivery part from which fuel flows to the burner, fuel receiving means movably supported and arranged to intermittently dip into said reservoir part for periodically transferring fuel therefrom past said barrier to the delivery part, an instrumentality for effecting operation of said means thereby to transfer fuel in sufficient amount to sustain operation of the burner at low fire, further fuel receiving means similarly supported and arranged for periodically transferring fuel from the reservoir part past said barrier to the delivery part, and an instrumentality for effecting operation of said further fuel receiving means thereby to transfer fuel in a sufficiently increased amount to produce higher fire.

9. In combination, a liquid fuel burner, a source of liquid fuel supply, a fuel feeding system, a barrier separating said system into a reservoir part to which fuel is supplied from said source and a delivery part from which fuel flows

to the burner, fuel receiving means movably supported and arranged to intermittently dip into said reservoir part for periodically transferring fuel therefrom past said barrier to the delivery part, an instrumentality for effecting operation of said means thereby to transfer fuel in sufficient amount to sustain operation of the burner at low fire, further fuel receiving means similarly supported and arranged for periodically transferring fuel from the reservoir part past said barrier to the delivery part, an instrumentality for effecting operation of said further fuel receiving means thereby to transfer fuel in a sufficiently increased amount to produce higher fire, and adjustment means for varying the transfer capacity of the fuel receiving means.

10. In combination, a liquid fuel burner, a source of liquid fuel supply, a fuel feeding system, a barrier separating said system into a reservoir part to which fuel is supplied from said source and a delivery part from which fuel flows to the burner, power operated fuel receiving means arranged to intermittently dip into said reservoir part and periodically transfer fuel therefrom past said barrier to the delivery part in sufficient amount to sustain operation of the burner at low fire, further power operated fuel receiving means similarly arranged and acting to transfer fuel from the reservoir part past said barrier to the delivery part in a sufficiently increased amount to produce higher fire, and control means governing the action of the power operated means.

JOSEPH R. KIRKPATRICK.
